DIE

Courtney R. Lindholm, St. Louis, Mo., assignor to
 Independent Die and Supply Company, St.
 Louis, Mo., a corporation of Missouri

Application September 12, 1934, Serial No. 743,704

3 Claims. (Cl. 164—33)

This invention relates generally to dies and particularly to a stripping device for dies of the blanking type.

Dies of the blanking type which are largely used in the manufacture of leather goods, such as gloves, and in many other industries, are ordinarily provided with a stripping device so arranged that the cut material, either the cuttings or the blank, is forced away from the cutting edges of the die after the die has penetrated one or more thicknesses of the material to be cut. Ordinarily such stripping devices are resiliently mounted so as to be biased in a direction toward the edges of the die. In order to prevent the stripping device from being forced outwardly beyond the edges of the die some means is ordinarily provided for limiting the outward movement of the stripper so that it is usually held substantially flush with the edge of the die. Heretofore various means, such as telescoping members, chains and the like, have been provided for this purpose.

The use of chains as the means for limiting the movement of the stripper with such dies has been attended with considerable difficulty for various reasons. In the first place, the chains are subject to considerable stretching so that after a relatively short period of use the stripper may be permitted to extend outwardly beyond the cutting edge of the die and thus interfere with its proper functioning. Moreover, the chains do not lend themselves to adjustment within short ranges, but such adjustment as is permitted is limited by link lengths and consequently proper adjustment of the stripper is difficult to obtain. Moreover, fouling of the chains with adjacent parts is not uncommon.

The object of the present invention, generally stated, is to provide a die of the character referred to with a stripper limiting means which is not subject to the objections above mentioned.

A further object of the present invention is to provide a stripper limiting means for a die of the character referred to which is formed of a strip of flexible, substantially non-stretchable, fibrous material.

A more specific object of this invention is to provide a stripper limiting means for a die of the character referred to which is formed of textile webbing.

Other objects will become apparent to those skilled in the art when the following description is read in connection with the accompanying drawing, in which:—

55 Figure 1 is a perspective view of a die for a

glove thumb having a stripper constructed and arranged in accordance with the present invention;

Figure 2 is a longitudinal section taken along line 2—2 of Figure 1, and illustrating more in detail the stripper operating mechanism of the die;

Figure 3 is a cross sectional view taken along line 3—3 of Figure 1.

In accordance with the present invention dies of the blanking type which are ordinarily provided with a resiliently mounted stripper arranged to be biased toward the cutting edge of the die so as to eject therefrom the cut material, either in the form of cuttings or blanks, may be provided with a means in the form of a strap for limiting the movement of such stripper toward the cutting edges of the die which strap is sufficiently flexible to permit a wide amplitude of movement of the stripper without fouling, is non-stretchable so that the adjustment of the stripper relative to the cutting edge remains the same, even after a long period of use and is such as to lend itself with facility to adjustments of any desired extent. In accordance with the present invention, cotton webbing may be employed for this purpose.

Referring now particularly to the drawing, there is illustrated in Figure 1 a blanking die of a shape suitable for use in cutting blanks of a shape and size for the making of thumbs of gloves and the invention will be described with particular reference to such die, although it is to be understood that the invention is not limited to any particular type of configuration of die.

As shown in Figure 1, the die may comprise a blade 1 having a cutting edge 2 extending entirely therearound. On the interior of the cutting edge 2 and in slightly spaced relation thereto is a stripper plate 3 arranged for movement axially of the die, but normally biased into a position where it is substantially flush with the cutting edge on the die, as shown, so that upon release of the pressure of the device in which the die is operated, the stripper plate 3 is effective to eject blanks from the interior of the die, it being understood that in usual operation the die may penetrate a number of thicknesses of material, such as leather, at one blow.

As clearly shown in Figures 2 and 3 across the top of blade 1, that is to say the edge remote from the cutting edge 2, is a top plate or cross piece 4 which may be suitably connected to the blade 1 as by screws 5 threaded into bosses 6, the latter being integral with blade 1. Extending upwardly from blade 4 is a plurality of studs 7, two being

- shown but it being understood that any number 5 may be provided, over each of which is placed a coil spring 8. The other end of the coil spring 8 may be seated against the inside of the stripper plate 3 and, as shown, may be inserted in suitable cups 9 in order to prevent slippage of the spring on the stripper plate. It will be apparent that the action of springs 8 is to bias the stripper plate 3 toward the cutting edges 2.
- 10 In accordance with the present invention, means is provided for limiting the outward movement of stripper plate 3 under the action of spring 8, and for this purpose one or more strips of a flexible, non-stretchable material, such as 15 cotton webbing, may be provided. The strips of webbing 11 are suitably secured by any desirable clamping means to the top plate or cross piece 4 and are likewise secured to the inside of the stripper plate 3.
- 20 Referring particularly to Figure 3, it will be observed that the strips of webbing 11 are folded over at their respective ends 12 and 13 so as to provide a double thickness against which the clamping device can operate. A suitable form of 25 clamping device is illustrated in the drawing and may comprise a bolt 10 extending through stripper plate 3 and through both thicknesses of the strip of webbing 11. Above the folded webbing may be provided a washer 14 illustrated in the 30 form of a plate which, if desired, may be provided on the underside with teeth or serrations which may take more firmly into the webbing, and upon the end of bolt 13 may be threaded a nut 15 drawn down sufficiently tight to prevent the webbing from slipping. Similar clamping 35 arrangements may be provided at the lower ends of the respective strips of webbing for clamping the same against the top plate 4. Such an arrangement permits the length of strip 11 to be 40 readily adjusted so that the movement of the stripper plate 3 may be limited to any desired extent which may be, for instance, substantially flush with cutting edges of the blade 1.
- 45 Suitable means such as a rib 16 may be provided on the exterior of blade 1 for connecting the die assembly with an operating press or the like.
- 50 From the foregoing description it will be understood that when the die is operated it is forced by a suitable source of pressure through a plurality of thicknesses of a material, such as leather, and that as the die is forced into the material to be cut, stripper 3 will move inwardly within the die so as to accommodate the cut blanks on the 55 interior of the die. Such a position of the stripper as illustrated by the dotted lines in Figure 3 where it will be noted that the stripper 3 has moved substantially one-half of the depth of the die. This movement is against the force of spring 8 so that when the pressure of the operating device is relieved, springs 8 expand and force stripper plate 3 back outwardly toward the edges 60 2 of the die, thus ejecting the cut blanks from

the interior of the die. When the die has penetrated the various thicknesses to be cut, it will be observed that the strips of webbing 11 have been bowed outwardly and in the embodiment illustrated, as shown particularly in Figure 3, the respective strips of webbing are so connected to the clamping device that the one on the left bows toward the left, and the one on the right bows toward the right so that they are entirely free of each other and there is no tendency for fouling. These strips, however, when the stripper plate has been forced outwardly under the action of springs 8 limit the outward movement of the stripper to any desired position.

From the foregoing description it is apparent 15 that the present invention accomplishes its objects and that a stripper limiting device is provided which, although flexible enough to permit an extreme amplitude of the stripper is, nevertheless, substantially non-stretchable so that an 20 adjustment once made continues for a long period of time and is also capable of being adjusted within exceedingly fine variations. It is further apparent that the invention is applicable to various types and configurations of dies and it is to 25 be distinctly understood therefore that the invention is not limited to the specific details of structure which have hereinbefore been set forth. It is to be distinctly understood, therefore, that such modifications and the use of such individual 30 features and sub-combinations of features as do not depart from the spirit of this invention are, although not specifically described herein, contemplated by and within the scope of the appended claims.

Having thus described the invention, what is 35 claimed is:

1. In combination, a blanking die having a stripper cooperating therewith to remove the cut material from the edges of the die, resilient 40 means forcing said stripper outwardly of said die, a continuous flexible non-stretchable band limiting the outward movement of said stripper, and means for adjusting said band in order accurately to position said stripper.

2. In combination, a blanking die having a 45 stripper cooperating therewith to remove the cut material from the edges of the die, resilient means forcing said stripper outwardly of said die, a continuous flexible non-stretchable band limiting the outward movement of said stripper, and clamping means for anchoring said band adjustable in minute increments along the band whereby accurately to position said stripper.

3. A die having a cutting edge and provided 50 with a stripper, means for moving said stripper into stripping position, and a strap of flexible but substantially non-stretchable material connecting said stripper with said die for limiting the movement of said stripper with respect to the 55 cutting edge of said die.

COURTNEY R. LINDHOLM.
